United States Patent Office.

THEODORE THURBER, OF AUBURN, NEW YORK.

Letters Patent No. 63,185, dated March 26, 1867.

IMPROVEMENT IN PISTON PACKING.

The Schedule referred to in these Letters Patent and making part of the same.

TO ALL WHOM IT MAY CONCERN:

Be it known that I, THEODORE THURBER, of Auburn, in the county of Cayuga, State of New York, have invented certain new and useful improvements in a Self-Regulating Equilibrium Pressure Packing Piston for steam cylinders, gas or water engines, pumps, &c., and the following is a full, clear, and exact description of the same, reference being had to the accompanying drawings, making a part of this specification, in which—

Figure 1 represents a cross-section through the piston head, showing the metal packing-ring, internal flange-plate, ring-cap, the two valves for admitting the steam, gas, or water into the recess, to press equally on the entire inner surface of the packing-ring, and the spiral spring, to hold the valves off their seat when no pressure is on them.

Figure 2 shows a plan or top view of the spider or skeleton-head with the end cap removed.

Figure 3 is an enlarged detached view of valves.

The object of my invention is to introduce the most simple, cheap, and durable self-pressure regulating metallic piston packing for locomotive and other engines, by which the pressure under the packing-ring of the piston is reduced from fifty to seventy per cent. per inch less than the pressure in the boiler, and this reduced pressure being kept uniform the whole length of the stroke, thereby making the wear uniform the entire length of the cylinder, which is not the case with other steam packing not so regulated.

My invention consists in the construction of the internal flange-plate A, ring-cap B, between which the packing-ring C may be placed without expanding, they forming a narrow, steam-tight recess, *a a*, surrounding the piston. Also, in the arrangement of two double-faced valves, *e e*, acting on one spiral spring, *d*, equally by the pressure on either side of the piston, so that the steam, gas, or water forced into the recess *a a* is not exhausted at each stroke, the internal pressure on the packing-ring C being regulated by and is equal to the force of the spring *d* that holds the valves *e e* to their seats inside of the recess.

To enable others to make and use my invention, I will describe it more fully in its construction and operation.

The spider-plate E, the internal flange-plate A, ring-cap B, and face-plate F are the most plain and simple iron castings, which are easily turned off and fitted in a common engine lathe. The metal packing-ring C may be forged of steel or may be cast of other metal, and fitted in the same manner. In both the flange-plate A and the ring-cap B are the seats for the small cone valves *e e*, which have stems, *ff*, and a shoulder, *ii*, to bear on the inside of the rings *bb* and rest on the spiral springs *d* which may be of any required capacity to allow the pressure from either side of the piston H through the small orifice *hh* to act on the valves *e e*, thus admitting as much force of steam, gas, or water into the recess *a a* as the resistance of the spring *d* will yield to, and then the apertures are closed by the cone valves *e e*, and kept so as long as the pressure outside in the cylinder is greater than the resistance of the spring *d*, so that the force in the recess *a a*, which acts directly and equally against the entire surface of the metal ring packing C, is kept uniform in the same ratio of from fifty to seventy per cent. per inch less than the pressure in the cylinder or boiler, this being obtained by the area or opening around the stem between the two faces of the valves *e e*, together with the distance or space in which the valves move. Other advantages to be derived by a steam piston packing from which the steam is not exhausted from under the packing-ring at each stroke, are, that the piston in vertical or beam engines may be retained in any desired position when stopped, so as to enable the engine to be started back or forward without the necessity of bringing the piston to near the centre of the cylinder, as would be the case when allowed to exhaust; or, by a greater weight on either crank or piston to cause the same to approach either head of the cylinder during the halt or ordinary stopping of marine engines. It has been practically demonstrated that a very large percentage of the power is saved by the means above described over any other mode of metallic packing for pistons known and used.

Having thus described my invention, what I claim, and desire to secure by Letters Patent, is—

1. The construction of the internal ring-plate A, with ring-caps B fitted, leaving a steam chamber or recess, *a*, between them and the metal ring packing C, so that it can be put in its place without opening or expanding, substantially as described.

2. I claim the two valves *e e* as constructed, in combination with the ring-plate A and cap B, operating from both sides or faces of the piston, they being supported by the spring *d*, so that steam, gas, or water forced into the chamber *a* is not exhausted or liberated at each stroke, the internal force being retained, thereby producing the result, substantially as herein specified.

3. I claim the combination of the skeleton frame and plate E, flange-plate A, ring-cap B, face-plate F, metal packing-ring C, valves *e e*, and spiral spring *d*, all constructed and arranged to operate substantially as and for the purposes herein set forth.

THEODORE THURBER.
